UNITED STATES PATENT OFFICE.

CHARLES WILLIAM FIELD, OF ROCKLAND, MAINE.

DESIGN FOR A NAIL-SET.

SPECIFICATION forming part of Design No. 26,463, dated December 29, 1896.

Application filed November 23, 1896. Serial No. 613,206. Term of patent 7 years.

To all whom it may concern:

Be it known that I, CHARLES WILLIAM FIELD, a citizen of the United States of America, residing at Rockland, in the county of 5 Knox and State of Maine, have invented and produced a new and original Design for Nail-Sets, of which the following is a specification, reference being had to the accompanying drawings, forming a part thereof.

10 In the drawings, Figure 1 is a plan view of the nail-set, and Fig. 2 is an elevation thereof.

The leading features of my design are as follows: The point of the set is tapered, as shown at *a*, and at the head of this tapered 15 portion is a swell or enlarged portion *b*. A short distance from the upper end or head of

the set is a similar swell or enlarged portion *b'*, and the portion between these two points where the set is grasped by the hand rounds outwardly slightly, as shown at *c*. Above the 20 enlarged portion *b'* is another enlarged portion or bead *b''*, and above this the set tapers slightly to a head *d*.

I claim—

The design for a nail-set herein shown and 25 described.

In testimony whereof I affix my signature in presence of two witnesses.

CHARLES WILLIAM FIELD.

Witnesses:

S. T. KIMBALL,
S. F. KAVANAGH.
